A. M. Olds.

United States Patent Office.

A. M. OLDS, OF NEW YORK, N. Y.

Letters Patent No. 73,749, dated January 28, 1868.

IMPROVEMENT IN FOLDING BASKET.

The Schedule referred to in these Letters Patent and making part of the same.

TO ALL WHOM IT MAY CONCERN:

Be it known that I, A. M. OLDS, of the city, county, and State of New York, have invented a new and improved Folding Basket; and I do hereby declare that the following is a full and exact description thereof, reference being had to the accompanying drawings, and to the letters of reference marked thereon, which form part of this specification. In said drawings—

Figure 1 is a view in perspective of my folding basket when adjusted for use.

Figure 2 is a view of the bottom of the same disconnected.

Similar letters of reference indicate like parts.

This invention consists in so constructing a basket that it may readily be folded compactly, when not in use, as may be desired.

In said drawings, A may represent horizontal slats, the ends of which being connected together by means of wires B, passing through them, serving for hinges when adjustments are made. Angles are formed in said wires at requisite points for holding the bottom pieces C C, passing through the same, near their outer edges. These two bottom pieces are made a little wider than the space to be occupied, so that when their inner edges are brought together inside, they will support the contents of the basket, one edge being grooved to prevent a separation, if the pressure should not be uniform, (see fig. 2.) A hook or brace, D, is pivoted to one of the slats, so that when the basket is adjusted for use, it may be attached to another side of the basket in a diagonal direction, and hold it rigidly in its position. The slats are made uniform, or nearly so, in width, so that each side will fold into the spaces opposite compactly. At the lower corners of the basket, short pieces or sections, E, are secured, so as to allow room for the bottom to fold together with the sides, said bottom pieces being held in a folded position by a pin, F, pressing into the opposite piece. The ends of the wires B being bent over or riveted at the upper corners of the basket, secure all of the parts together, making a cheap and compact article for general use, which it is believed will be universal, both as a basket and a berry-crate. The sides of the basket may be constructed so as to stand in a vertical position, or any angle desired, or the bottom may be constructed of a single piece, and arranged so as to be detached before folding. Said bars or slats represented by A, may be constructed of sheet metal or wire, and looped around the corner wires, or otherwise be attached, so as to form the hinge referred to.

Having thus described my invention, what I claim, is—

1. As an improvement in the art of constructing baskets, boxes, or crates, forming the sides of a series of slats or bars, united at the corners by means of a wire or rod passing through them, and pivoting the same together, so as to permit the article to be folded, substantially as described.

2. I claim also the folding bottom, when constructed and arranged to operate substantially as set forth.

A. M. OLDS.
